S. B. HASELTINE

RESILIENT SHACKLE

Original Filed Sept. 12, 1923

Fig. 1

UNITED STATES PATENT OFFICE.

STACY B. HASELTINE, OF CHICAGO, ILLINOIS, ASSIGNOR, BY MESNE ASSIGNMENTS, TO
W. H. MINER, INC., A CORPORATION OF DELAWARE.

RESILIENT SHACKLE.

Application filed September 12, 1923, Serial No. 662,214. Renewed January 12, 1927.

This invention relates to improvements in resilient shackles.

The object of the invention is to provide a resilient shackle adapted to cushion both draft and buff shocks and which is more especially adapted for mine cars.

In the drawing forming a part of this specification, Figure 1 is a vertical, longitudinal, sectional view taken centrally through two adjacent mine cars showing my improvements in connection therewith. Figure 2 is a horizontal, sectional view corresponding substantially to the broken section line 2—2 of Figure 1. Figure 3 is a vertical, transverse, sectional view corresponding to the section line 3—3 of Figure 1. And Figure 4 is a detail plan view of one of the yoke-acting plates employed with my construction.

In said drawing, each of the mine cars as shown is provided with a heavy flooring 10, the latter being preferably cut away at one end of each car as indicated at 11, to provide a pocket to better accommodate the improved shackle. At the opposite end of each car, the flooring is cut away on a straight line transversely of the car as indicated at 111, to permit the shackle to be swung out of the way to a position at right angles to the axis of the car. Each car is further provided with attaching plates 12 and 13 secured to the upper and lower sides of the flooring, respectively, said plates having vertically aligned openings to accommodate the usual coupling pin 14, said openings being elongated longitudinally of the car to allow inward movement of the pins with respect to the adjacent car. As shown in Figure 1, the upper plate 12 is preferably upwardly offset in order to provide a greater vertical space between said plates to accommodate the shackle proper and the plate 13 at that end of each car having pocket to accommodate the shackle has the end portion thereof outwardly and downwardly inclined to facilitate the entrance of the shackle between the same and the corresponding plate 12.

The improved shackle comprises, broadly, an outer casing or shell A; a centrally disposed yoke B; two yoke plates C—C; and a spring resistance D.

The casing A is of rectangular cross-section having top and bottom walls 15—15, side walls 16—16, and a transverse end wall 116, said casing being open at the opposite

end. The top and bottom walls 15 are provided with vertically aligned sets of elongated openings 17—17 at each end through which extend the coupling pins 14, said slots being of a length to permit the desired compression stroke of the mechanism. The end wall 116 is adapted to coact with an angular buffering plate 117 at the corresponding end of the car, said plate having the vertically disposed portion thereof abutting the outer end of the floor, the horizontal portion of the same being secured to the upper surface of the floor 10 by bolts, or any other suitable fastening devices. As clearly shown in Figures 1 and 2, the closed end of the casing A has its opposite sides rounded off to permit the necessary free radial swinging movement, and the top and bottom beveled to facilitate entrance between the plates 12 and 13.

The yoke member B is preferably in the form of a relatively heavy casting having a central spring pocket 18 defined by side arms 19—19 and transversely extending end sections 20 and 21. The end section 20 has an elongated opening 22 therein through which extends a corresponding coupling pin 14, said opening being of a length to permit the desired compression stroke of the mechanism. The other transverse section 21 of the yoke B is provided with a vertically extending, somewhat elongated recess 23 open at the end facing the spring pocket and within which is slidably accommodated, the other coupling pin 14. At the outer end of the section 20 is provided a flat transverse buffering face 120 adapted to coact with a buffer angle 121 at the corresponding end of the floor of the adjacent car, said angle 121 being in the form of a heavy plate, having the vertically disposed portion thereof abutting the end of the floor and the horizontal portion fixed to the latter by bolts or any other suitable means. The section 20 is rounded off at opposite sides adjacent the face 120 to permit of the necessary free radial swinging movement of the shackle.

The two plates C are of like construction and each comprises a flat plate section proper 24, from the inner side of which is extended a vertical flange 25, near one end thereof, 105 said flanges 25 being vertically aligned when the parts are assembled as shown in Figure 1. Outwardly of the flange 25, each plate 24 is provided with an integral extension 124 of restricted width offset toward the center or 110

axis of the mechanism and having a rounded end face adapted to abut the inner face of the end wall 116 of the casing A. On the same side of the plate section 24, the latter is cut 5 away as indicated at 26 to form a partial seat for the spring resistance D. Between the flange 25 and the adjacent end of the plate C, the latter has an elongated slot 27 within which is accommodated one of the 10 coupling pins 14. Similar slots 28 are provided near the opposite ends of the plates C to accommodate the other coupling pin 14.

The spring D is inserted within the pocket 18 of the yoke B and between the top and 15 bottom plates C, one end of said spring bearing upon the transverse section 20 of the yoke B and the other end bearing upon the two flanges 25 of the yoke-acting plates C.

Means is also preferably provided to retain the shackle in position at right angles to the car when uncoupled; and the car is being handled in a restricted space as for example, when on the mine hoist. This means preferably consists of a pair of brackets 29 20 in the form of angle plates secured to one end of each car at opposite sides thereof, and a pair of bosses 30 at opposite sides of the casing A, extending downwardly from the bottom wall thereof, each adapted to cooperate with a recess 31 in the horizontal portion 32 of one of the angle plates 29. The angle plates 29 are preferably secured to the vertical portion of the buffer plate 121, having the vertically extending portion thereof riveted or otherwise secured thereto. The outer edge portions of the horizontal sections 32 are preferably curved downwardly and adapted to engage with and guide the bosses 30 when the shackle is swung to either 35 side, each boss being provided with a beveled portion 33 to cooperate with the curved edge of the corresponding bracket 29. Each boss 40 is so positioned with reference to the pin 14 about which the shackle is swung, that it will drop into the opening 31 of the corresponding bracket 29 when the shackle is moved to either position at right angles to the axis of the car, and retain the same in said position, the casing A being directly supported 45 by the horizontal portion of the bracket.

With the parts assembled as shown in Figure 1, it is evident that, upon a compression action, and assuming the right hand car to remain stationary the buffing angle 117 will 50 be brought into engagement with the casing A and the casing A, together with the yoke-acting plates C, will move toward the right, thus compressing the spring D against the transverse section 20 of the yoke B which is held stationary by engagement with the buffing angle 121. Similarly, upon a draft 55 action and still assuming the right hand car stationary, as the left hand car moves toward the left, the yoke B will be pulled thereby, thus compressing the spring between

the transverse section 20 and the flanges 25, the latter being held stationary by the right hand coupling pin 14, as is also the casing A, in this instance.

From the preceding description considered in connection with the drawing, it will be observed that the shackle is adapted for pivotal movement in the event the cars travel over curved sections of track; and that the spring and yoke members are completely housed within the casing A. All of the parts are of simple construction, readily adapting them for economical manufacture. Furthermore, the entire arrangement is such that it may be readily applied to mine cars now in service without material alteration to the car and at small expense.

I have herein shown and described what I now consider the preferred manner of carrying out my invention but the same is merely illustrative and I contemplate all changes and modifications that come within the scope of the claims appended hereto.

I claim:

1. In a resilient shackle of the character described, the combination with yoke means adapted to be connected with one vehicle to transfer the pulling and buffing strains thereto, said yoke means being adapted to abut said vehicle at a place other than at its point of connection thereto; of another yoke means adapted to be connected to an adjacent vehicle to transmit pulling and buffing strains thereto; cushioning means operatively interposed between said two yoke means; and connecting elements for effecting connection of said shackle to said vehicles, each of said elements extending through both of said yoke means, said yoke means being movable relatively to said connecting elements to compress said cushioning means in buff and draft.

2. In a resilient shackle of the character described, the combination with yoke means and a coupling pin adjacent one end thereof for pivotally connecting the latter to a vehicle, said yoke means being engageable with said vehicle beyond said pivotal connection thereto; of another yoke means having a portion disposed on the outer side of said pivotal connection, and a coupling pin adjacent the opposite end of said second yoke means for pivotally connecting it to a second adjacent vehicle; and cushioning means operatively interposed between said two yoke means, said last named yoke means being engageable with said last named vehicle beyond the pivotal connection thereto, said first named yoke means having a portion operatively extending on the outer side of said latter pivotal connection.

3. In a resilient shackle, the combination with a substantially rectangular yoke member having a spring pocket therein and a coupling pin for pivotally connecting the

same to one vehicle; of additional yoke-acting means comprising two plates slidably mounted on opposite sides of said first named yoke member, and a coupling pin for pivotally connecting said plates to the end of an adjacent vehicle; and a spring operatively interposed between said yoke member and yoke acting plates.

4. In a resilient shackle, the combination with a casing; of a pair of oppositely disposed yoke-acting plates, disposed within said casing; a second yoke member slidably mounted between said plates and also within said casing, all of said parts being adapted for attachment to adjacent vehicles; and a spring within said casing operatively interposed between said yoke member and the yoke plates.

5. In a resilient shackle of the character described, the combination with a casing having vertically alined slots near each end thereof to accommodate coupling pins, one end of said casing being adapted to engage with the end of the adjacent car to prevent movement of said casing in one direction; of a pair of upper and lower plates within said casing each having correspondingly disposed and alined openings to accommodate said coupling pins, said plates having oppositely extending flanges near one set of ends thereof; a yoke member slidably mounted between said plates and having a spring pocket therein, one end of said yoke member being adapted to engage with the end of the adjacent car to prevent movement of said yoke member in one direction.

6. In a resilient shackle of the character described, the combination with a casing having vertically alined sets of elongated openings at each end thereof; of a pair of upper and lower plates disposed within said casing and having correspondingly alined

slots, said plates having engagement with one end of said casing; a yoke member slidably mounted between said plates and having a spring pocket therein; follower acting flanges on said plates; and a spring interposed between said flanges and the opposite end of said yoke member and means for operatively attaching said shackle to adjacent cars.

7. In a car, the combination with a shackle including a casing, yoke means disposed within said casing, and a second yoke member slidably mounted relatively to said means; of means for connecting the shackle to the car for swinging movement in a horizontal plane, whereby, the shackle may be swung out of the way to a position at right angles to the car; a bracket fixed to the adjacent end of the car adapted to support said shackle when swung to said position; and inter-engaging retaining means on said shackle and bracket.

8. In a resilient shackle of the character described, the combination with a yoke having means for engaging one end of a spring; of a secondary yoke acting means adapted to engage the opposite end of said spring; a spring interposed between said yoke and said yoke acting means; a housing enclosing the whole; means at opposite ends of said yoke and said yoke acting means for attaching same to adjacent vehicles, and for imparting the pulling strains through said members to said springs; and means independent of said attaching means whereby said yoke and said yoke acting means may be moved relatively to absorb the buffing shocks.

In witness that I claim the foregoing I have hereunto subscribed my name this 8th day of September, 1923.

STACY B. HASELTINE.
